UNITED STATES PATENT OFFICE

144,381

DESIGN FOR AN ADVERTISING DISPLAY FIGURE OR THE LIKE

Caroline D. Holmes, Scituate, R. I., assignor to Buckley & Scott, Inc., a corporation of Rhode Island

Application August 9, 1945, Serial No. 121,337

Term of patent 14 years

(Cl. D1—2)

To all whom it may concern:

Be it known that I, Caroline D. Holmes, a citizen of the United States of America, residing at Scituate, county of Providence, State of Rhode Island, have invented a new, original, and ornamental Design for an Advertising Display Figure or the like, of which the following is a specification, reference being had to the accompanying drawing, forming a part thereof.

Fig. 1 is a front elevation of an advertising display figure or the like showing my new design; and

Fig. 2 is an edge view of the same.

The essential features of my design reside in the portions shown in full lines.

I claim:

The ornamental design for an advertising display figure or the like, substantially as shown and described.

CAROLINE D. HOLMES.
